W. ARKIN.
ARTIFICIAL TOOTH.
APPLICATION FILED JUNE 12, 1916.

1,203,298.

Patented Oct. 31, 1916.

Inventor:
William Arkin,
By his Attorney,
Lee H. Midd.

UNITED STATES PATENT OFFICE.

WILLIAM ARKIN, OF NEW YORK, N. Y.

ARTIFICIAL TOOTH.

1,203,298.

Specification of Letters Patent. Patented Oct. 31, 1916.

Application filed June 12, 1916. Serial No. 103,061.

To all whom it may concern:

Be it known that I, WILLIAM ARKIN, a citizen of the United States, and a resident of the borough of Bronx, city of New York, county of Bronx, and State of New York, have invented certain new and useful Improvements in Artificial Teeth, of which the following is a specification.

My improvements relate to what are known in dentistry as "detachable" teeth, in which provision is made for detachably securing a porcelain or other artificial tooth to a base, crown, bridge or other support, in such manner that a new front or tooth may be substituted for one that is worn or broken without the destruction or injury of the base or support.

The invention consists in the specific construction of parts described and claimed.

In the accompanying drawings, Figure 1, is a side elevation of a tooth attached to a base by means of my coupling-mount, the base being shown in cross section; Fig. 2, is a rear view of the tooth, the base being omitted; Fig. 3, is a central vertical section of the tooth, mount, and base or backing; Fig. 4, is a front elevation of a portion of the backing, the tooth being omitted; Fig. 5, is an elevation of the outer or receiving end of the mortise or socket piece; Fig. 6, a side elevation thereof; Fig. 7, an elevation of the inner end of the mortise or socket piece; Fig. 8, a section taken upon plane of line 8—8, Figs. 5 and 7; Fig. 9, is an elevation of the outer end of the tenon piece; Fig. 10, is an elevation of the inner end thereof; Fig. 11, is a side elevation thereof; Fig. 12, is a section taken upon plane of line 12—12, Fig. 9; Fig. 13, is a view like unto Fig. 3, showing the tenon piece on the base or backing protruding into a tooth socket formed in one piece with the tooth; Fig. 14, is a sectional view of the one piece socket tooth shown in Fig. 13.

In the above named drawings, for convenience of illustration the parts are shown upon an enlarged scale.

The artificial tooth A, is made of porcelain or any other suitable material in the usual way except that it is formed on its rear side with a socket or mortise m. This mortise is formed in a projecting lug or tenon and may be formed in one piece with the rest of the tooth A, as in Figs. 13 and

14, or it may consist of a metallic mortise 55 embedded therein, as in the other figures of the drawing, in which case the mortise m^o, may be constituted by a section of tubing, preferably of flattened character in cross section,—i. e., having two diameters, one considerably longer than the other. The mortise is also preferably, although not necessarily, rectangular in cross section as shown in the drawings; and when made as a metallic insert its inner edges are spread and outward turned to form flanges or shoulders m', m', which, act as anchors to retain and hold the socket or mortise piece firmly embedded in the tooth. The anchor shoulders m', m', may be of angular, barbed or irregular form 70 to insure intimate and rigid contact with the material in which they are embedded. In either case, whether made in one piece with the artificial tooth or embedded therein, the side walls of the mortise m, are integral 75 therewith, and said side walls are also made to protrude, as at m^x, beyond the back side of the tooth A.

The coupling pin or tenon t, is embedded in the base B, which latter may be part of a 80 bridge, crown, or other backing or support of any kind. The tenon t, is formed with a head having an inturned flange t', creating a recess t², for the reception of the outer edges m^x, of the walls of the mortise m^o, as shown 85 more particularly in Figs. 1, 3, and 13.

As indicated by cross hatching in Figs. 6, 10, and 11, the surfaces of both socket pieces m, and tenon piece t, may be roughened in any suitable manner to increase frictional 90 contact and adhesiveness.

The outer end of the tenon t, may be recessed as at t², Figs. 3, 9, and 12, when the coupling parts are arranged as shown in Fig. 3, for the purpose of affording more 95 space for cement and to obviate as far as possible any visual indication of the presence of the coupling through the porcelain, which is more or less translucent.

My improved form of coupling affords 100 ample security for the tooth which is held rigidly in position on the base or backing, while should the tooth become unduly worn, broken or impaired in any way it may be readily removed by ordinary dental tools 105 and appliances, and another substituted in lieu thereof without injury to the supporting backing. In this connection it is to be

noted that while coincident angularity of contour is desirable in the construction of the copulative parts to insure strength and rigidity, still I do not wish to limit myself thereto, since an oval or flattened form in cross section might be resorted to without departing from the spirit and intent of my invention.

By the use of my coupling device a tooth or facing may be easily removed and another substituted in lieu thereof without removing the supporting appliance from the patient's mouth where such appliance has been originally made and provided with my improved artificial tooth as herein set forth. Furthermore by this means the danger of cracking the porcelain while soldering the bridge or support is obviated because the facing or teeth may be mounted and cemented in position on the bridge or supporting appliance after the completion of the latter. Another advantage attained by the use of my invention and the consequent ease of replacement of teeth is that all necessity for reinforcing the teeth with gold tips, etc., is obviated, thereby avoiding the exceptionally artificial appearance of such tipped teeth. Finally, and most important of all, my improved form of artificial tooth is especially adapted as an article of manufacture for dental trade and practice, since it can be effectually and cheaply made as a stock article for embodiment with any suitable form of dental appliance,—the tenon t , and recess t^2 , being formed on and in the backing by the practising dentist to meet the particular conditions and requirements in each case, as may be found most expedient.

It will be seen that the distinctive feature of applicant's invention consists in the combination of an artificial tooth formed with a rear socket other than circular in cross section and having protuberant side walls, and a base or backing recessed to receive, accommodate, and fit said protuberant socket side walls and also formed with a tenon fitting the tooth socket as herein set forth.

By making the interlocking copulative parts other than circular in cross section I effectively lock them against lateral play or looseness and reinforce them in this respect against the strain to which they are subjected during the use of the tooth.

What I claim as my invention and desire to secure by Letters Patent is,

1. A dental mount of the character designated, comprising an artificial tooth having a hollow tenon projecting therefrom and a base or backing having a tenon adapted to fit within the hollow tenon of the tooth.

2. A dental mount of the character designated, comprising an artificial tooth formed with a rear mortise integral therewith, said mortise being other than circular in cross section and having side walls projecting beyond the back of the tooth, and a base or backing formed with a tenon embedded and firmly held therein and adapted to engage and fit said mortise in the tooth, and being also recessed to accommodate and fit the protuberant side walls of the mortise on the tooth, for the purpose described.

3. A dental mount of the character designated, comprising an artificial tooth formed with a projecting rear mortise integral therewith, said mortise being angular in cross section, and a base or backing formed with a tenon embedded and firmly held therein and adapted to engage and fit said angular mortise in the tooth, for the purpose described.

4. A dental mount of the character designated, comprising an artificial tooth formed with an integral projection having a mortise extending into the body of the tooth, and a backing provided with a tenon and engageable in said mortise, said mortise and tenon being other than circular in cross section.

5. A dental mount of the character designated, comprising an artificial tooth formed with a projection with a mortise extending into the body of the tooth and a backing having a tenon and embedded therein and having a head with inturned flange forming a recess for the reception of the outer edges of the walls of said mortise.

6. A dental mount of the character designated comprising an artificial tooth portion formed with an integral lug mortised to receive a tenon, said mortise being angular in cross section, and a base or backing having a tenon secured therein and shaped to be received in said mortise.

WILLIAM ARKIN.
